COMBINATION STOVE AND FIREPLACE

Jerome P. Tripp, Middleboro, Mass., assignor to Bay State Crucible Company, Taunton, Mass., a corporation of Massachusetts

Filed May 11, 1964, Ser. No. 79,914

Term of patent 14 years

(Cl. D81—7)

FIG. 1

FIG. 3

FIG. 2

FIG. 4

FIG. 5

FIG. 6

FIG. 1 is a perspective view of a combination stove and fireplace showing my new design;

FIG. 2 is one side elevational view thereof;

FIG. 3 is a top plan view thereof;

FIG. 4 is the other side elevational view thereof;

FIG. 5 is a rear elevational view thereof; and

FIG. 6 is a bottom plan view thereof.

The exhaust pipe shown in broken lines is included for illustrative purposes only.

I claim:

The ornamental design for a combination stove and fireplace, substantially as shown and described.
